PHOTOGRAPHIC CLIP AND SUPPORT

Anthony Ludwig, Falls Church, Va.

Application November 28, 1950, Serial No. 197,885

4 Claims. (Cl. 95—100)

1

This invention relates to photographic clips and supports and particularly to those clips and supports adapted for use in processing long or short strips, such as photographic films.

In the making of photographic negatives, the films are passed successively from one tank containing a processing solution to another tank containing another processing solution, after which the films are washed and dried.

In the processing of ordinary black and white negatives, the films are first placed in a tank containing a developing solution. After the film is developed, it is usually placed in a so-called "short stop" solution which arrests, at once, all action of any developer solution which may have remained on the film. After treatment in the "short stop" solution, the film is removed and placed in a hypo solution. This hypo solution removes all of the light sensitive portion of the emulsion on the film body which has not been affected by the light exposure. This completes the processing except for washing and drying of the negative.

After the hypo treatment, the negative is removed from the hypo solution and placed in a water bath. In some laboratories it is customary to use two hypo baths—first a weaker bath and then a stronger bath. The negative, before passing to the dryer, may be put through one, two, or more water baths to be sure that all of the hypo has been removed.

In removing a clip with its negative from one solution to go into another, it is obvious that it is advantageous if the clip is so shaped as to cause practically all of the solution to run off as the clip and its negative emerge from the surface of the solution. This is important because (1) there is a minimum loss of solution and (2) there is a minimum contamination of the next solution. And when the negative has finished being washed, there is less water to be removed by evaporation.

Also, in developing and washing photographic films, particularly film packs, considerable trouble has been encountered due to other causes. The clips have collected and held water until after the films were dried and when disturbed, have given up the water to be deposited on the films. This causes the emulsion to be distorted when dried the second time and when printed, transmits the appearance of a drop of water. Further, the film pack films have come in contact with the racks, often resulting in a sticking of the films to the racks. On removal, the silver deposit usually found on the racks has had a

2

tendency to adhere to the film, thus practically destroying its usefulness. To avoid this retention of the water on the clips to be later, perhaps accidentally, deposited on the film, some laboratories have installed an additional bath with what is called a "wetting agent." This bath may contain "aerosol" or some similar agent whose function it is to destroy the surface tension of the water, promoting its draining from the clips. 10 This extra bath would be useless if the water drained properly from the clips.

With the clips in use at the present time, for example in photographic development, there has been found to be a definite tendency for the clips to hold on their surfaces, the liquids such as chemicals and water, for a longer time than desirable after having been removed from the chemical or water bath.

In the case of the chemicals, too much of the liquid chemical is drawn out on the surface of the clip, thus wasting the chemical and unnecessarily contaminating the next bath into which the film and its clip may be inserted. In the case of the water, too much of the water adheres to the clip after passing through the final water bath. This often results in the retention of much water on the clip after the film is thoroughly dried. The result of such a condition is that upon removal of the film and clip from the drying rack, the water retained on the clip is disturbed and runs onto the film. This water rewets the film and may result in (1) streaks on the film or (2) damage to the film, made possible by contact after being softened by the water and (3) tear drop marks as already pointed out.

In any event, this surplus chemical solution or water is undesirable on either the clip or its support.

The primary object of this invention is the provision of an improved photographic clip and support therefor.

Another object of the invention is the provision of an improved clip which has its parts so shaped that when immersed in liquid and then withdrawn, the liquid will substantially all run off of the clip as withdrawn from the liquid, thus facilitating the drying of the film.

Still another object of the invention is the provision of a clip so shaped as to minimize the collection of liquid thereon, due to surface tension.

A still further object of the invention is the provision of a clip having a minimum amount of surface close to other parts of the clip and to parts of the supported object.

Another and still further object of the invention is the provision of a clip having its parts so shaped as to drain liquid away from the gripping portions of the clip.

Another and still further object of the invention is the provision of an improved clip wherein there are a plurality of gripping means, each having a plurality of gripping teeth arranged in relative positions to be in a substantially vertical line when in use.

Another and still further object of the invention is the provision of an improved clip which will be free from cup portions upturned U-shaped portions or hollow spaces or horizontal surfaces, or horizontal lower edges which would assist the normal surface tension of a liquid to retain the liquid on the clip.

Another and still further object of the invention is the provision of a clip having jaws so formed as to have small area contacts with the object, such as a film being dried, thereby permitting a uniform rate of drying of the film with the consequent avoidance of a wet portion at the clip and the necessity of cutting off of its wet ends as the film is removed from the racks.

Another and still further object of the invention is the provision of a sheet metal photographic clip having its side edges so formed as to drain and discharge substantially all of the processing liquids and water as the clips with their films are withdrawn respectively from the processing tanks and water baths.

Another and still further object of the invention is the provision of a sheet metal clip wherein are provided no inclosed or substantially inclosed spaces where ventilation and efficient drying would be retarded.

Another and still further object of the invention is the provision of a clip wherein each of its lower extremities comes substantially to a point to facilitate prevention of formation and retention of drops and promotes discharge of the liquid as the clips leave the tanks.

Another and still further object of the invention is the provision of a sheet metal clip wherein all of the body of the clip, except its upper loop, will be in substantially vertical planes, thus promoting the draining of the processing liquids from the surface of the clip as the clip is withdrawn from the liquid.

Another and still further object of the invention is the provision of a clip and support construction where films or similar articles may be suspended substantially in a vertical plane and without contact therewith except at the jaws of the clip.

Still another and further object of the invention is the provision of a clip and support for drying films and which has substantially all vertical surfaces, the support having vertical and cross bars with clips thereon to support film pack films making contact only with the clips and at the corners with cross bars.

Still another and further object of the invention is the provision of a clip which may be used with the gripping means at either top or bottom and in either position will have the lower edges of its sides out of horizontal with their lowest points having substantially no length or width.

Still another and further object of the invention is the provision of a clip having oppositely disposed arch portions which will drain liquids regardless of which arch is upright.

Other and further objects of the invention will be apparent to one skilled in the art from a reading of the complete specification.

Referring to the drawing wherein is illustrated an embodiment of the invention,

Fig. 1 is a front view of the clip on an enlarged scale.

Fig. 2 is a side view of the invention as illustrated in Fig. 1, with a part section on the line 2-2 of Fig. 1.

Fig. 3 is a detail enlarged view of a modified form showing the details of the gripping device.

Fig. 4 is an enlarged view of the lower ends of one pair of the gripping elements at a right angle to Fig. 3.

Fig. 5 is a pattern of the blank of the end of the modified clip end of Figs. 3 and 4.

Fig. 6 is one form of support with clips attached, for developing and processing film pack films.

Fig. 7 is a side view of Fig. 6.

Fig. 8 is one form of support bar with clips attached.

Fig. 9 is an end view of Fig. 8.

Fig. 10 is a fragmental view of the front elevation of a modified form of clip which will efficiently discharge any liquid from its surface, regardless of which end is on the top.

Fig. 11 is a side view of Fig. 10.

Fig. 12 is a sectional view taken on the line 12-12 of Fig. 11.

Similar reference characters refer to the same or similar parts throughout the specification and drawing. The clip will first be described.

The numeral 10 designates the main body of the clip which is of sheet material and bent so as to form a spring loop to provide resilience to operate the gripping means as will be later described. The forward depending portion 10a of the main body portion ends in two depending portions 10b, 10c, each of which forms a portion of a gripping means for holding an article, as a film 12. Each depending portion 10b, 10c is provided with one or more ribs 10d, for coaction with the complementary portion of the gripping means to be presently described. The depending portion 10a and the ends 10b, 10c are in a substantially vertical plane.

The rear depending portion 10e of the spring body portion 10 is provided with a pair of arms 10f which are substantially in vertical planes when the clip is supported in its normal operative depending position. These arms 10f extend on each side of the forward depending portion 10a of the main body portion 10 and have downwardly extending ends 10g which are provided with prongs or teeth 10h which preferably have their axes pointing diagonally upwardly with their points in registry with the space at or slightly below the center of the respective ribs 10d. The upper edges of these prongs 10h are preferably sloped downwardly from the points and their lower edges have a greater slope.

On the lower edge of the arm 10f is a cut-in edge 10i which is located above the teeth 10h and serves as a stop or limiting means for the upper edge of the film 12 when the latter is inserted in the clip, yet has sufficient slope to conduct the liquids downwardly toward the bottom of the clip.

The normal spring tension of the main body portion 10 of the clip is such that the prongs 10h or teeth 10h are normally held with their re-

spective points, each in registry with a rib 10d. By having the ribs slightly longer than the width of the sharp point of the teeth 10h, it is obvious that any slight accidental bending of the teeth or the arms 10f will still leave the points of the teeth in registry with its rib 10d.

The lower ends of the downwardly extending ends 10g of the arms 10f provided with points 10k, whose tips are away from the object, as a film, which is being supported. This feature drains the liquid on the clip away from the film and permits even a small drop to leave the clip. A further advantage of this construction is that the edge between the point 10k and the lower tooth 10h acts as a guide to the film when it is being inserted in the clip.

In this connection it is to be noted that the top and bottom edges of the arms 10f are inclined downwardly toward the tips 10k, thus tending to facilitate the clearing of the liquid from the clip. The pointing of the teeth 10h in an upwardly inclined direction, tends to grip the film, or other object, firmly and also tends to drain the liquid away from the film and toward the tips 10k. The spring pressure of the teeth 10h is such that the film will be gripped and firmly held but not perforated.

The lower extremities of the depending portions 10b and 10c terminate in substantially pointed ends, 10m, 10n, which extend backwardly and away from the normally depending position of the film which further tends to drain and discharge the liquid from the clip when the latter with its film is removed from a bath.

The clip supporting frame illustrated on Figs. 6 and 7 will now be described.

Each supporting frame is provided with a bar 50 which is of sufficient cross section to support the depending film-holding structure and of sufficient length to extend over the top and beyond the sides of any developing machine with which it is designed to be used.

Spaced from the ends are preferably a pair of depending vertical bars 51. Connecting these vertical bars 51 are a series of superimposed horizontal thin bars 52 arranged in substantially a vertical plane to permit a minimum amount of liquid to adhere thereto when the rack and films are withdrawn from a chemical solution or water bath.

These transverse horizontal bars 52 are spaced apart a sufficient distance to permit of the hanging of the film pack films from the clips. These clips which have already been described, per se, are secured to the transverse bars 52 by any suitable manner as by spot welding the back side portions to the sides of the bars 52.

In connecting the clips to the frame, I have carried out the idea of providing a support and a clip for the same which will shed the liquid of any chemical or water bath in connection with which the frame may be used. To bring about this result, there is a direct relation between the vertical width of the cross bar and the height and attached position of the clip on the transverse bar 52. It is to be noted that the height of the clip is sufficient to permit the loop of the body portion 10 to be above the upper edge of the transverse bar 52. In addition, the lower portion of the clip extends below the lower edge of the transverse bar 52 so that the edge 10i which limits the upper position of the film, when in place, is high enough so that the clips occupy spaces on and with relation to the bars 52, such that the tops of the film pack films

will be slightly above the lower edge of the bar. In this way, with the emulsion side toward the bar, the upper corners of the negative will curl against the bar and tend to hold the negative 5 nearer to its normal plane.

It is to be noted that with the loop of the body portion 10 of the clip above the upper edge of the transverse bar 52 and the upper edge of the film occupying a place high enough to barely contact the transverse bar 52, the jaws 10h with the ribs 10d will hold the film entirely clear except at the corners and the points where the film is held, and without piercing the film.

Referring particularly to Figs. 8 and 9, where there is illustrated a slightly modified form of the gripping mechanism, the parts 110f, 110g, 110h and 110k are similar to the parts 10f, 10g, 10h and 10k as illustrated in Figs. 1 and 2, and as previously described.

At the lower end 110b of the front folded portion 110a, the gripping member is of slightly different construction from the corresponding portion of Fig. 1. In Figs. 8 and 9, the lower end 20 of the portion 110b, for example, terminates in a portion 110p which has three folded teeth 110q, corresponding to the three ribs 10d, already described. In this construction, the teeth 110h register with spaces just slightly below the corresponding points of the teeth 110q so that the film when between the teeth 110h on one side and the teeth 110q on the other, will be made to assume somewhat of a very slight wave formation with sufficient spring pressure between the teeth 110h and 110q to hold the film in place without causing it to be perforated. As shown in Fig. 8, the teeth 110q are much wider than the teeth 110h. In practice the degree of sharpness of the teeth 110h and 110q may be varied, if desired, to suit the conditions to be met. In some instances the contacting edges of the teeth 110q may have such a small degree of sharpness that they may be shaped similar to the contacting portions of the ribs 10d. And if the ribs 10d are made to protrude sufficiently, they may be considered as being teeth.

The lower end of the lower portion 110b ends in a point 110m for a purpose similar to the point 10m already described.

Referring to Figures 1 to 4, which illustrate both forms of the invention, the ribs 10s and 110s may be provided as stiffening means for the portions 10f and 110f respectively. Also, the ribs 10t and 110t may be provided on the lower side extensions of the front folded portions 10a, 110a, respectively, for a similar purpose. These ribs 10t, 110t extend outwardly toward the tips 10n, 10m, 110n and 110m to give proper stiffening action to the corresponding gripping portions of the clip. These stiffening ribs 10s, 10t and 110s, 110t may be made with the first step in the stamping process.

The modified form of clip illustrated in Figs. 10, 11 and 12 will now be described.

In photographic film processing it may be desirable that one type of clip be used for both the top and bottom of the film while the film is progressively passing through the chemical solutions and water baths of the developing machines. The form of clip illustrated in Figs. 10 to 12 fills this requirement.

In this form, the bow of the clip is provided with a cross section which will shed water and discharge it at a point of very small horizontal area, regardless of which end of the clip is at the top. This permits of the use of the clip at the

top or bottom of the film being processed, as desired.

Referring particularly to Figs. 10 to 12, the top of the clip is illustrated as having a bow shaped resilient portion having a forward extension 210a extending from the bow on one side and a rear extension 210e from the other side.

The curved portion of the bow has its central portion 210u cut out while on each side of the cut-out space is a curved rib portion 210v stamped in the remaining curved straps of the curve of the bow. On one of the vertical extensions, as 210e, may be placed a weight 210w which is so formed, as of a diamond shape, and so placed that any liquid present on its surface will be quickly conducted to its lower corner and thence to the then lower end of the clip, regardless of which clip end is at the top.

Considering the clip in the position as shown in Figs. 10, 11 and 12, when withdrawn from a liquid bath, the liquid in the upper sides or troughs of the portions 210v will immediately be shed onto the front of the front extension 210a and the liquid on the rear of the center of 210v will, at once, drain from its trough onto the outside of the rear extension 210e. The liquid on the undersides of the arch portion 210v, as shown in Fig. 11, will be at once conducted to the inner sides of the extensions 210a, 210e, and thence to the lower portions of the clips and discharged from the lower clip ends. These lower ends, here not shown, may be constructed according to the showings of the Figs. 1, 2 or Figs. 3, 4, as already described.

Considering this clip being used as a bottom clip, the parts illustrated as being at the top of Figs. 10, 11 and 12, would be at the bottom of the clip. Any liquid, of a bath, which might be withdrawn with the clip would at once drain to the four lower points of the clip at the lower sides of the inverted arch portions 210v from which it would be discharged. Generally considered, the construction is one in which there is a double arch construction and one in which the lower end of each extension has substantially no horizontal length or width. This is the feature which always permits the clip to clear itself of liquid, regardless of which end is up. The double arch construction facilitates the quick draining of the liquid to the lowest portion of the clip and the fact that the lowest parts have practically no horizontal length or breadth causes the liquid to be at once discharged.

It is thus clear that this clip may be used at either end of a film to be processed.

It will be noted that the objects of this invention have been well attained. The material for rack and clip may be of stainless steel or any suitable metallic or non-metallic material. By having the small rib portions 10d at the lower ends of the arms for contact on one side of the film, for example, and the upwardly pointing prongs or teeth 10h in contact with the other side of the film, the liquid chemicals or water will drain from the clip, thus insuring a dry clip when the film is dry. This action is assisted by having no horizontal or near horizontal surfaces to collect or hold liquid, aided by surface tension, by having the lower ends 10m and 10k of the two gripping devices so shaped as to drain the liquid away from the clip as soon as it is removed from the bath, by having the film gripped by the teeth of the gripping means and in a vertical line and by shaping the teeth so as to facilitate the natural draining of the liquid to the points

110k, 110m. It will be noted that the lower edge 110i is slightly inclined to drain the liquids to the bottom of the clip.

The elongated rib portions 10d and teeth points 110g insure proper co-action with the teeth 10k and 110k even though the latter may be slightly bent.

In Figs. 8 and 9 there is illustrated a supporting bar 50a having a series of loops 50b depending therefrom for the purpose of supporting the clips 10. This adaptation of the clip is for carrying strip films 12 as indicated in these figures in dotted lines.

While the disclosure herein made has been in detail and in connection with a photographic film, it is to be understood that this disclosure is merely illustrative, that it has other possible uses and that further modifications and changes than those illustrated may be made without departing from the spirit of the invention and within its scope as claimed.

In the claims, the expression "complete liquid drainage" is used. This is not intended to include that liquid which may adhere to the surface of the clip as a film, held by capillary attraction. This film will readily dry off. The term is intended to cover drops which because of the shape of the clip will be drained off. In this way, at the end of the drying of the film-negative, there will be no drops to become dislodged and fall on the negative after it is dry.

Reference is made to my co-pending application No. 661,099, filed April 10, 1948, now forfeited, of which this is a continuation in part.

Having described my invention, what I claim is:

1. A film-negative carrying means including a support, a spring-clip secured to the support, the clip having an inverted U-shape and having uninter-spaced pairs of gripping means with uninterrupted space therebetween, the surfaces of the support and clip having downwardly extending surfaces throughout, the adjacent parts of the surfaces of the clip being so spaced and angularly placed as to provide complete liquid drainage to the lower end of the clip and provide clear ventilation throughout the surfaces to prevent the formation and retention of drops of liquid on the support and clip.

2. A film-negative carrying means including

a support, a spring-clip secured to the support, the clip having an inverted U-shape and having uninter-spaced pairs of gripping means with uninterrupted space therebetween, the surfaces of the support and clip having downwardly extending surfaces throughout, the adjacent parts of the surfaces of the clip being so spaced and angularly placed as to provide complete liquid drainage to the lower end of the clip and provide clear ventilation throughout the surfaces to prevent the formation and retention of drops of liquid on the support and clip, each pair of gripping members being set with relation to each other so as to cause the gripping of the film and film gelatine between the gripping means of a pair, with a non-piercing action on the film itself.

3. A film-negative carrying means including a support, a spring-clip secured to the support, the clip having an inverted U-shape and having uninter-spaced pairs of gripping means with uninterrupted space therebetween, the surfaces of the support and clip having downwardly extending surfaces throughout, the adjacent parts of the surfaces of the clip being so spaced and angularly placed as to provide complete liquid drainage to the lower end of the clip and provide clear ventilation

tion throughout the surfaces to prevent the formation and retention of drops of liquid on the support and clip, each gripping means of a pair having a relative setting to its complementary gripping means which will prevent piercing of the film by the gripping means, one of the gripping means being sufficiently sharp to only enter the surface of the gelatine of the film-negative.

4. A film-negative carrying means including a support, an inverted U-shape sheet metal clip having a fold at its upper end and two pairs of film-gripping means at the lower end of the clip, one gripping element of each pair of film-gripping means being connected to each fold, one of the folds having one element of each pair of gripping means at its lower end, the other fold having two arms at its sides and extending at the sides of the first fold in a downwardly inclined direction and having a coacting gripping element at the lower end of each arm and complementary to and in vertical planes normal to the first mentioned gripping elements, the first mentioned elements having protruding portions and the second mentioned elements having teeth respectively co-acting with the protruding portions, the lower ends of the gripping elements narrowing at their bottoms to conduct liquid off the clip surface when the clip is removed from the liquid bath.
